Primary Examiner — Cynthia Underwood(74) *Attorney, Agent, or Firm* — Westman, Champlin & Koehler, P.A.(57) **CLAIM**

The ornamental design for a filament spool, as shown and described.

DESCRIPTIONFIG. 1 is a top perspective view of a filament spool;
FIG. 2 is a top view thereof, where a bottom view is identical to the top view;

FIG. 3 is a front view thereof, where a rear view is identical to the front view; and,

FIG. 4 is a right side view thereof, where a left side view is identical to the right side view.

The features shown in broken lines illustrate environmental subject matter only, and form no part of the claimed design.

1 Claim, 3 Drawing Sheets---
